Patented June 27, 1922.

FIG. I

FIG. 3

FIG. 2

INVENTOR
CLARENCE B. ROGERS
BY *Paul & Paul*
HIS ATTORNEYS.

UNITED STATES PATENT OFFICE.

CLARENCE B. ROGERS, OF SEATTLE, WASHINGTON, ASSIGNOR TO M. F. PATTERSON DENTAL SUPPLY COMPANY, OF ST. PAUL, MINNESOTA, A CORPORATION OF ILLINOIS.

BUNSEN ATTACHMENT FOR BLOWPIPES.

1,420,947.

Specification of Letters Patent. Patented June 27, 1922.

Application filed July 31, 1919. Serial No. 314,572.

To all whom it may concern:

Be it known that I, CLARENCE B. ROGERS, a citizen of the United States, resident of Seattle, county of King, State of Washington, have invented certain new and useful Improvements in Bunsen Attachments for Blowpipes, of which the following is a specification.

The object of my invention is to provide 10 a blow pipe having a head on which the tip may be conveniently mounted, said head being of such construction that it will form a supporting base for the tip and hold it in an upright position, or may be used as 15 a means for hanging up the tip when the burner is not in use.

A further object is to provide a form of tip on which a Bunsen burner may be easily and quickly mounted.

20 Other objects of the invention will appear from the following detailed description.

The invention consists generally in various constructions and combinations, all 25 as hereinafter described and particularly pointed out in the claims.

In the accompanying drawings forming part of this specification,

Figure 1 is a vertical sectional view 30 through a blow pipe tip and burner embodying my invention,

Figure 2 is a sectional view on the line 2--2 of Figure 1,

Figure 3 is a sectional view on the line 35 3--3 of Figure 1,

In the drawing, 2 represents a suitable tube through which the mixture of gases for the blow pipe is conducted. 3 is a base having a passage 4 therethrough communicating with the tube 2 and with the passage 5 of a tip 6 that is tapped into the upper end of the base. The base is preferably flat on the bottom and has a flange 7 thereon provided with a hole 8 and with recesses 9 for hanging up the base on a nail or hook or other suitable supporting means. The walls of the base are of sufficient thickness and weight to support the tip in an upright position. This allows the tip to be placed 50 on a table or bench where it will stand upright without any other supporting means

than the base and allow the convenient use of the device for uniting pieces of metal, porcelain or other material.

The walls of the passage 5 through the 55 tip have annular steps 10 which are inclined to direct the gases inwardly to the center of the passage and insure a complete mixture thereof before reaching the end of the tip.

The tip is tapered, as shown, and I prefer to provide a Bunsen burner 11 having a tapered socket to receive the tip so that whenever desired it may be mounted on the tip for use in connection with the blow pipe 60 for various purposes. This burner is provided with the usual sleeve-like upper portion 12 and the series of ports 13 in the walls thereof near the base. The base supporting the tip may, of course, be made in 65 various sizes and shapes, according to the use for which the device is intended, and there may be any suitable amount of metal in the base, sufficient to render the upright tip stable under all conditions.

In some instances it may be desirable to use the tip in a horizontal position and by providing the base as herein shown I am able to suspend the tip in this way and have both hands free for supporting the metal 70 or other material to be united.

I claim as my invention:

1. A blow pipe tip and a base therefor having means for connection with a gas supply and provided with a surface for 85 supporting the tip in an upright position, and said base having means for hanging it and the tip on a suitable support said means including openings formed in the edge of said base upon opposite sides of said tip 90 and a hole in said base intermediate said openings.

2. The combination, with a blow pipe tip, of a base whereon said tip is mounted, a gas tube connected with said base, and a 95 flange radiating from said base and having diverging openings therein upon opposite sides of said tip for suspending the base.

In witness whereof, I have hereunto set my hand this 19th day of July 1919.

CLARENCE B. ROGERS.
